UNITED STATES PATENT OFFICE.

ISIDOR KITSEE, OF PHILADELPHIA, PENNSYLVANIA.

POLYCHROMATIC SCREENS INTEGRAL WITH MOVING-PICTURE FILMS.

Original application filed July 26, 1921, Serial No. 487,633. Divided and this application filed February 21, 1922. Serial No. 538,328.

To all whom it may concern:

Be it known that I, ISIDOR KITSEE, citizen of the United States, residing at Philadelphia, in the county of Philadelphia and 5 State of Pennsylvania, have invented certain new and useful Improvements in Polychromatic Screens Integral with Moving-Picture Films, of which the following is a specification.

10 My invention relates to an improvement in polychromatic screens integral with moving picture films.

This application is a division of application filed July 26, 1921, Serial No. 487,633.

15 The accompanying drawing illustrates a device with the aid of which I have produced integral polychromatic screens on moving picture films of different lengths. Some of the films were perforated, before 20 the production of the integral screen and on some of the films I produced integral screens without perforating the film.

In this drawing Fig. 1 is a top plan view 25 of the device, with part of the film inserted therein. Fig. 2 is a transverse vertical section taken on line 2—2 of Fig. 1. Fig. 3 is a vertical longitudinal section taken on line 3—3 of Fig. 1. Fig. 4 is a vertical section taken on line 4—4 of Fig. 1. Fig. 5 is a fragmentary plan view of part of the film.

In these drawings, 1 is the support or base on which the device used by me is mounted. 2 is the race-plate adapted to guide the film during the passage, so that the same may not 25 deviate to right or left. This race-plate is held in position by the blocks 3—3 secured with the aid of the screws 4—4 to the support. 5 is the pressure plate, performing the office of keeping the film when passing 40 through the race-plate in the desired flattened position. This pressure plate is secured to the race plate with the aid of the adjustable screws 6—6 in conjunction with the springs 7—7 to produce an exact adjustment of the pressure required. The support 45 1 is either fastened to a working bench directly or is provided, as shown in the drawing with legs 8—8. 9 is an angle plate secured to the base 1 and provided with a cut-out part or machine slide 10. In this machine slide is positioned the carrier 11, supporting and carrying the cutter or knife 12. This cutter or knife is shown here as comprising four series of cutting knives 13, 13, 55 13, 13. Each series consists of a number of

knife edges and the whole series is of a width substantially equal to the width of a film from perforation to perforation. The width of each of the knives of each series corresponds to the width of the line it is desired to produce on the film. In some of the cutters made, each series consists of from 120 to 160 knives, spaced from each other substantially the width of each of the knife edges. The cutter is secured to the adjustable carrier 11. 14 are the adjustable means as an entirety for raising and lowering the carrier 11 and therefore the cutter 12. These adjustable means comprise here the micrometer screw 15, the means 16, here shown as a conventional knob, to manipulate the screw, the dial 17 provided with the gradations 18 and the zero mark 19, having its counter part on the stationary block 20.

In the drawing is also shown the film 21 in the process of being wound from the spool 22, carried through the race plate and in operative relation to one of the series of knives 13 and the means to draw the same through the race plate and in cutting contact with the different knife edges. This means 23 is here shown as a fragment of a pulley supposedly centered in a revolvable shaft and rotated—preferably with the aid of an electric motor. In practice, the speed of the pulley should be comparatively great and as I have found it advisable to use a pulley of rather comparatively large diameter, I employed intermediate means to obtain the required speed of this pulley.

In Fig. 5, 21 is part of a film as an entirety and of this film 24 represent the cut-out parts and 25 the parts not cutout. These uncut parts are provided, as will hereinafter be more clearly explained with the tinted 95 surface 26 and the coating 27.

It has to be stated that the pressure plate 5 is provided with an aperture 28, so as to allow the edges of the stationary cutter to come in operative relation with the film 100 proper.

The mode of operation in producing the integral screen is substantially as follows: I take it for granted that the film on which the screen is to be produced is about 200 feet 105 in length (as most of the films come in lengths of 200 or 400 feet); I also take it for granted that one surface of the film is, as usual, coated with gelatine. The first step is to tint the uncoated surface with the re- 110

quired color, dissolved in a medium adapted to attack the celluloid of the film. In producing the film, I make use of a dye dissolved in alcohol and add thereto an equal 5 quantity of ether. I carried this film through the dye-bath with the aid of a revolving drum and after the film has been passed through the dye-bath and has been dried, the tinted surface is covered with a temporary 10 protective layer, such as gelatine, and after drying it is wound around a spool, such as is shown in the drawing at 22.

The film is then threaded through the race 15 plate of the device. All parts, pressure plate, the cutter and such other parts as are necessary are properly adjusted, so that when the film is drawn through the race plate the different knives of the cutter will 20 cut into the film in a manner, so as to remove the protective coating and the tinted part of the surface. The film will then represent a surface with clear lines in intaglio and tinted and protected lines in relief.

With the aid of a drum or similar device 25 the film is then drawn through a second dye-bath of a color different from the color of the first dye-bath, but of a nature adapted to attack the celluloid now laid bare.

I use for the second bath a dye dissolved 30 in alcohol and add thereto about an equal quantity of ether. After drying, all coatings were removed with the aid of water, slightly higher than normal temperature.

Having now described my invention, what 35 I claim as new and desire to secure by Letters Patent is:

1. The method of producing integral screens upon cinematographic film, which method consists in tinting one of the sur-

faces of the film, then coating said tinted 40 surface with a protective coating, and then with the aid of stationary cutters removing said protective coating and the underlying tinted surface of the film along unbroken 45 longitudinal lines.

2. The method of producing integral screens upon cinematographic film, which method consists in tinting one of the surfaces 50 of the film, then coating said tinted surface with a protective coating, then with the aid of stationary cutters removing said protective coating and the underlying tinted surface of the film along unbroken longitudinal lines, then tinting the cleared lines with a tint different from the first tint, and then 55 removing the remaining protecting coating.

3. The method of producing integral screens upon cinematographic film, which method consists in causing on a previously 60 tinted film, the surface thereof protectively coated, to be produced in one and the same operation a series of longitudinal and unbroken clear lines with the aid of stationary cutting edges, causing then the so produced clear lines to be tinted in a color different 65 from the first tint, whereby longitudinal unbroken lines of one tint are produced, interspersed by longitudinal unbroken lines of a different tint.

4. In the art of producing integral screens 70 upon cinematographic film, the step which consists in causing with the aid of a series of stationary cutting edges, a series of clear unbroken lines to be produced on a formerly tinted film interspersed by unbroken lines of 75 the former tint.

In testimony whereof I affix my signature.
ISIDOR KITSEE.
